UNITED STATES PATENT OFFICE.

FREDERIC E. BERTRAND, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

METHOD OF MAKING REINFORCED INSOLES.

1,272,902.

Specification of Letters Patent. Patented July 16, 1918.

Original application filed September 25, 1911, Serial No. 651,056. Divided and this application filed October 8, 1915. Serial No. 54,765.

To all whom it may concern:

Be it known that I, FREDERIC E. BERTRAND, a citizen of the United States, residing at Lynn, in the county of Essex and State of Massachusetts, have invented certain new and useful Improvements in Methods of Making Reinforced Insoles; and I do hereby declare the following to be a full, clear, and exact description of the invention, such as will enable others skilled in the art to which it appertains to make and use the same.

This invention relates to a method of making insoles and more particularly to a method of making reinforced insoles.

The novel insole produced by the method hereinafter described, its method of manufacture, and a machine for performing the steps, in the process of its manufacture, incidental to the application of the reinforcing material, are disclosed in applicant's application for Letters Patent of the United States, Serial No. 651,056, filed September 25, 1911, from which this present application is a division.

In the early life of reinforced insoles the type having the greatest commercial success was the "Gem" disclosed in the patent to Cole No. 575,460, dated January 19, 1897. Later other types of reinforced insoles were developed such as the "Economy" disclosed in the patent to Johnson No. 849,245, dated April 2, 1907, and the "Wonder-Worker" disclosed in the patent to Ryan No. 958,013, dated May 7, 1910, and to some extent in the earlier patents to Krippendorf No. 579,518, dated March 23, 1897, and Bohr No. 878,453, dated February 4, 1908. The "Gem" insole was a better insole than the "Rochester" insole, disclosed in the patent to Moore No. 275,248, dated April 3, 1883, which preceded it, because in the Gem the reinforcing fabric is carried across the feather thus stiffening this exceedingly flexible portion of the insole and preventing its becoming curled up under the upper in the lasting and subsequent operation on the shoe. For this reason, also, the commercial supremacy of the Gem insole has been generally maintained since the introduction of the Economy type of reinforced insole because this type is open to the same criti-

cism as the Rochester insole, that is, an unreinforced feather is used, which is a serious defect on thin stock. At the same time the Economy insole is an improvement on the Gem insole because of the greater strength of the marginal lip or rib and because the stock at both the inside and outside of the lip is of the same thickness, making for a tighter seam and for less damage to the reinforcing fabric during the inseaming operation, as is well understood by those skilled in the art. Another, and a serious, defect in the Gem insole, which the later types of reinforced insoles overcome, is that the duck or canvas, used as reinforcing fabric, is trimmed in such manner that its raveled edge shows beyond the edge of the insole and gives an unsightly appearance to the inside of the finished shoe. It has more recently been proposed to combine some of the good features of the Economy and Gem insoles in a single insole and some manufacturers are now using an insole blank having a marginal lip or rib like that of the Economy insole and a sheet of reinforcing fabric applied thereto like that of the Gem insole. An illustration of this type is found in Figure 3 of the Thoma Patent No. 1,108,026, dated August 18, 1914. Still this reinforced insole, which may be termed the "Cincinnati" insole is imperfect because it does not overcome the serious defect of the fabric showing, at the shank of the insole especially, in the finished shoe.

The object of the present invention is to improve the manufacture of insoles in such a manner as to produce a reinforced insole in which the reinforcing fabric is so applied as to overcome the defects in the completed insole due to an improper application of the fabric such as hereinbefore adverted to.

To the accomplishment of this object the invention consists in the method of making reinforced insoles, the preferred manner of practising which is hereinafter described and defined in the appended claims.

An understanding of the invention will be assisted by reference to the accompanying drawing in which,

Fig. 1 is a transverse section across the forepart of an insole blank with its edge

slit as is customary in making a Gem insole;

Fig. 2 is a transverse section of the insole blank shown in Fig. 1 with a section formed by the edge slit turned up to form a marginal lip or rib;

Fig. 3 is a section showing the blank of Fig. 2 after having been reinforced by the present method, and

10 Fig. 4 is a plan, and

Fig. 5 is a section of an insole in the process of being reinforced by the tools of the machine of the prior application hereinbefore referred to.

15 In making the insole, the blank 2 which may be of leather or any other suitable material, is preferably slit at its edge as at 4 (Fig. 1) in a plane usually parallel to the face of the blank. The section 6, on the

20 flesh side, if the blank is of leather, is then upturned to form a marginal lip or rib (see Fig. 2) while the section 8 on the opposite, or grain side of a leather blank, forms the feather of the insole. Reinforcing fabric

25 10 which is preferably, although not necessarily, in the form of a wide sheet is then applied to the lipped face of the blank 2, being beaded or crimped about the lip or rib 6 and extending laterally to either side

30 thereof. The fabric may be applied by hand, or by any of the commercial machines supplied for performing this operation, and if applied by a machine, the machine illustrated in said application Serial No. 651,056

35 may conveniently be used.

The present method contemplates, more particularly, the production of a reinforced insole of the "Gem" type with the reinforcing fabric extending over and strengthening the feather outside the marginal lip or rib however said lip or rib may be formed, but having the excess marginal portion of the fabric severed along such a line that it lies within the edge of the blank. In other words, the fabric trimming operation is so performed that in the finished insole the outer margin of the feather is left uncovered by the fabric, through which expedient the threads at the severed edge of the fabric, 50 if they unravel, will not show beyond the edge of the insole after its incorporation in a shoe.

The step of trimming the fabric along the desired line may, obviously, be performed 65 at any convenient time. In some factories it may be expedient to perform this step after the fabric has been completely applied to the blank, and in others during the operation of applying the fabric. One convenient and effective mode of severing the fabric is disclosed in said application Ser. No. 651,056 hereinbefore referred to.

After the blank has been provided with a marginal lip or rib, for example in the manner disclosed in Fig. 2, reinforcing fabric is

roughly applied to the lipped face usually by running a blunt tool around the forepart, above the fabric, in the angle at the inside of the lip which leaves the marginal portion of the fabric extending outwardly above the lip, as shown at the lower half of Fig. 4. Thereafter the insole is operated upon by a machine, or machines, to complete the application of the reinforcing fabric and trim it to the desired size. The machine of said application, Serial No. 651,056 is preferably, although not necessarily, used to complete the application of the reinforcing fabric, and with this machine a severance of the fabric along the desired line may also be effected.

In using the machine of said application, and referring more particularly to Figs. 4 and 5, the insole is supported, while being operated upon, on a rotary work-feeding 85 table 12, over which it is fed by the machine.

The devices for operating on the insole supported on the work supporting table to crimp the reinforcing material into a bead and cause the reinforcing fabric to adhere 90 to the vertical lip of the insole consist of an inside former comprising a frusto-conical roll 14 arranged to press the reinforcing material against the inner face of the lip and against the face of the insole at the 95 base of the lip, and an outside former comprising a rotary wheel 18 arranged to press the reinforcing material against the outer face of the lip and against the feather. The roll 14 is mounted upon the lower end of a 100 vertical shaft 15 which is rotatably mounted in the machine frame and positively driven so that it will assist in feeding the insole forward. To this end the roll 14 is provided with longitudinal teeth 16. The shaft 105 19 on which the outside forming wheel 18 is mounted is also positively driven. The wheel 18 is provided with a beveled face 20 complementary to the sloping face of the conical roll 16. With the forming wheel and roll thus constructed and arranged, they will 110 act to compress the lip from base to top and bend the lip inward at an inclination to the surface of the sole so that it will stand at the proper angle to the bottom of the last for the convenient and proper lasting and sewing of the shoe when the sole is bent transversely in applying it to the curved bottom of the last. This arrangement of the lip engaging surface of the roll and forming wheel also insures the shaping and bending of the lip and reinforcing fabric so that the reinforcing fabric is pressed 115 firmly into the angles at each side of the lip or rib. It is thus seen that by employing the machine of said application but a single operation, in addition to the first rough application of the fabric, is needed to complete the application of the reinforcing fabric to the marginal lip or rib.

In order to avoid the necessity of a separate trimming operation the machine of said application is provided with a fabric-trimming knife 22 the support for which is mounted for oscillation upon the shaft 19 of the forming wheel 18. The knife blade is arranged so that when oscillated, its cutting edge severs the reinforcing fabric directly adjacent the outside edge of the wheel 18 where it bears upon the fabric. Thus the knife 22 severs the fabric along a line determined by the path of the outside edge of the wheel 18. In order that the line of severance may be within the edge of the blank, a forming wheel 18 is selected having a width preferably narrower than the narrowest width of the feather of the insoles to be operated upon. This results in the fabric being trimmed along a line within the edge of the blank. It will be observed that the arrangement described provides for a trimming cut at a uniform distance from the lip or rib. This, however, is not essential and the cut might be gaged from the edge of the blank with equally good results in the finished insole. The main advantage obtained by trimming the fabric in the manner just described is that because the free margin 24 of the sticky fabric outside the line of severance is not pressed into engagement with the outer margin of the feather before being severed it is easily removed from the insole during the trimming operation.

Those skilled in the art will understand that the important portion of the insole where the edge of the fabric should lie within the edge of the blank is at the shank, as the forepart is not easily visible, after the insole has been incorporated in a shoe; therefore, should the forming wheel 18 be equal in width to the width of the feather around the forepart, still an insole would be produced having the advantages hereinbefore described.

Those skilled in the art will also understand a particular advantage gained by the method herein described and claimed, namely, the severance of the fabric along a line within the edge of the blank in such manner that the full strength of the feather is retained. The feature of the method which permits a retention of the full feather strength is the location of the trimming knife above the feather in a position to merely incise the fabric along the desired line. As hereinbefore indicated by performing the fabric trimming step in this manner the excess fabric up to a line within the edge of the blank can easily be removed without the necessity of skiving, or otherwise cutting into and removing the stock of the feather with a consequent weakening thereof.

Having thus described the invention and

the preferred manner of practising it, what is claimed as new, is:

1. The method of making reinforced insoles which comprises providing a blank with an upstanding marginal lip or rib, applying reinforcing fabric to the lip or rib, and severing the fabric alone, during the fabric applying operation, along such a line that when the application of the fabric is completed its edge will lie on the feather within the edge of the blank. 75

2. The method of making reinforced insoles which comprises providing a blank with an upstanding marginal lip or rib, applying reinforcing fabric to the lip or rib, and severing the fabric along a line on the feather within the edge of the blank, at the shank portion of the blank at least, without a reduction of the thickness of the feather. 80

3. The method of making reinforced insoles which comprises edge slitting a blank, upturning one of the two sections to produce a lip and feather, applying reinforcing fabric to the lipped face of the blank, and severing the fabric along a line on the feather within the edge of the blank, at the shank portion of the blank at least, without a reduction of the thickness of the feather. 85

4. The method of making reinforced insoles which comprises cutting the marginal portion of the blank to produce a lip and a feather, and simultaneously applying reinforcing fabric to the lipped face of the blank, bending the lip inwardly and severing the fabric along a line on the feather within the edge of the blank. 95

5. That step in the method of making reinforced insoles which consists in severing the reinforcing fabric along a line on the feather within the edge of the blank without a reduction of the thickness of the feather. 105

6. That step in the method of making reinforced insoles which consists in applying pressure to the reinforcing fabric on the feather for a portion of the width of the feather measured outwardly from the lip or rib and simultaneously severing the fabric along a line substantially at the outer limit of the pressed area as it lies on the feather. 110

7. That step in the method of making reinforced insoles which consists in severing the marginal portion of the reinforcing fabric by an incision through the fabric from above where it lies over the feather along such a line that its edge, at the shank portion of the blank at least, lies within the edge of the blank. 120

8. The method of making reinforced insoles which comprises providing a blank with a marginal lip or rib and a feather of varying width outside of said lip or rib, applying reinforcing fabric to the lip or rib and feather, and severing the fabric alone along a line parallel to the lip or rib, 130

and within the edge of the blank at its shank portion at least.

9. The method of making reinforced insoles which comprises providing a blank 5 with an upstanding marginal lip or rib, applying reinforcing fabric to the lip or rib, and severing the fabric along a line on the feather within the edge of the blank, at the shank portion of the blank at least.
10. 10. A method of trimming the canvas on a reinforced insole, which consists in securing the canvas over the feather and cutting

through the canvas on the feather against the surface of the insole, without cutting away any of the body of the insole.

11. A method of trimming the canvas on a reinforced insole, which consists in securing the canvas over the feather and cutting through the canvas on the feather against the surface of the insole, inside of the edge 20 of the insole, without cutting away any of the body of the insole.

FREDERIC E. BERTRAND.
